BUMPER JACK

John L. White, Dallas, Tex., assignor to Robert C. Brown, Jr., Highland Park, Ill., as trustee

Application July 7, 1945, Serial No. 603,647

5 Claims. (Cl. 254—107)

1

This invention relates to lifting jacks and more particularly to a type of lifting apparatus known as a bumper jack.

The principal object of the invention is to provide an inexpensive but effective and durable jack, adapted primarily to lift vehicles for tire changes and other purposes by engaging the bumper of a vehicle and by virtue of a pair of spring pressed, circular elements or washers, loosely mounted on parallel uprights, together with a handle actuated oscillatable member, constrained to alternately rock the said washers on said uprights, a housing embracing said elements, having means for engagement under the object to be lifted, is caused to be moved upwardly on said uprights to lift said object.

Another object of the invention is to provide a lifting jack consisting of the few working parts named, but supplemented by a releasing lever located conveniently near the operating handle, having the function to center the washers on the uprights and, through the joint action of the said lever, springs and handle, the said housing is released to the weight of the object lifted to lower the latter.

With the foregoing objects as paramount, the invention has further reference to certain features of accomplishment which will become apparent as the description proceeds, taken in connection with the accompanying drawings wherein:

Figure 1 is a perspective view of a jack constructed according to the invention.

Figure 2 is an elevational view, fragmentarily showing the upright support and showing the housing in vertical section.

Figure 3 is a plan view in transverse section, taken on line 3—3 on Figure 2, a portion of the oscillatable shaft being broken away.

Figure 4 is a side elevational view, and

Figure 5 is a detail perspective view of the oscillatable shaft for actuating the washers.

Continuing with a more detailed description of the drawing, reference is primarily made to Figure 1 wherein numeral 10 denotes a stand formed by bending a rod or tubing of suitable diameter to define an elongated U-shaped member consisting of the parallel uprights 11. In the case of pipe or tubing, preferred for the reason that it is stronger, the upper ends 12 are flattened, as shown in Figures 1 and 2 which prevents the housing 13 from sliding off the ends of the uprights.

The housing 13 is of simple construction, consisting of two confronting U-shaped plates 14 whose meeting edges are held together by means

2

of a rectangular plate or strip 15 at the top and bottom, to which the inwardly turned edges of the plates 14 are spot welded at appropriate points. Thus, a rigid body, having open sides is provided and is apertured to slidably receive the uprights 11.

The plates 14 of the housing 13 are further provided with aligned slots below their midsections to accommodate a lifting arm consisting of two flat pieces of metal 16, welded together intermediate their ends and shaped to define a lifting arm 17. The pieces 16 extend entirely through the housing 13 and their rear ends are bent reversely at 18 and flattened against the outer surface of the plate 11 opposite the lifting arm 17. A shoulder 19 (Figure 4) is formed in the under edge of the arm 17 where it enters the housing 13 to serve as an abutment, reinforcing the arm 17 when a load is imposed thereon, the flattened ends 18 of the plates 16 preventing them from being drawn from their positions in the housing under stress of a load.

To raise the housing 13 on the uprights 11 with a series of successive movements, a "climbing" ring or washer 20 is mounted on each upright and whose central opening is slightly larger than the diameter of the uprights. Bearing upon the underside of each washer 20 is a coiled spring 21, surrounding the upright therebelow. The washers 20 are adapted to be alternately rocked on their uprights by means of an oscillatable stub shaft 22. This shaft has a reduced end 23, extending through an aperture in the housing wall 14 next adjacent the lifting arm 17. The opposite end of the shaft extends through an opening 24 in the opposite wall of the housing and, contributing to the structural economy and ease of assembly of the device, no means other than the washers 20, reposing in recesses 25 in the shaft 22, is required to hold the latter against longitudinal displacement in the housing.

The recesses 25 (Figure 5) are arranged longitudinally in shaft 22 on opposite sides thereof and in which the edges of the washers 20 are received in the manner shown. Sufficient clearance is allowed the edges in the recesses 25 to prevent binding thereof as the shaft 22 is oscillated.

One end of the shaft 22 is formed into a flattened pin 26, which is received by a correspondingly shaped recess in the end of a handle 27, the latter consisting of flat metal and is readily removable from the pin 26.

In operating the jack, the arm 17 is disposed under the object to be lifted, such as the bumper of an automobile and the lower end of the stand

10 is set into a base consisting of a channel member 28 whose sides 29 are bent slightly inwardly to more nearly equal the diameter of the uprights 11 in their relative spacing. The base prevents the stand from sinking into the ground and from sliding from under the load and a pin (not shown) inserted in holes α in the sides of the channel member 28, prevents displacement of the stand longitudinally of the base.

As the handle 27 is reciprocated vertically, the shaft 22 is oscillated, which action rocks the washers 20 on the respective uprights 11 alternately. For example, viewing the assembly as it appears in Figure 2; the shaft 22, is being rotated in a counter-clockwise direction, will raise the inner edge of the washer 20 at the right while the companion washer assumes the weight of the load imposed on the housing 13 by the supporting or lifting arm 17. As the change is made in the position of the washer on the right, the spring 21 thereunder retains the same and shifts it to a higher level on the upright. When the shaft 22 is rotated in the opposite or clockwise direction, the other washer is similarly actuated, the washer on the right being now effective to support the load and the spring under the active washer functioning to elevate the same. Oscillation of the handle and consequent rocking of the washers is continued until the object has been raised to the desired height.

To lower the housing 13 on the uprights 11, a release lever 30 is provided which is fastened, preferably by welding, to one of the washers 20. It will be observed, especially in Figure 3 that the free end of the lever 30 is bent at right angles to overlie the handle 27 in order that it may be engaged by the thumb of the same hand used to actuate the handle. By pressing downwardly with the thumb on the lever 30 to bring the washer to which it is attached into a horizontal position as the handle 27 is gradually lowered to such position as to dispose the companion washer also in a horizontal plane, a fixed angle member 31, depending from the upper end of the housing 13 will be engaged by the said companion washer, which latter, it will be understood is under the normal pressure of the spring 21 therebelow. With both washers now in a horizontal plane, they no longer function to support the housing 13, which latter, under the weight of the load supported by arm 17, falls downwardly with the load.

Manifestly, the construction as shown and described is capable of some modification and such modification as may be construed to fall within the scope and meaning of the appended claims is also considered to be within the spirit and intent of the invention.

What is claimed is:

1. In a lifting jack, a pair of parallel uprights, a washer rockably mounted on each of said uprights in substantially the same plane, springs surrounding said uprights below and bearing against said washers, a housing embracing said washers and springs, a shaft journaled in the walls of said housing to oscillate between said washers and having recesses receiving the edges of said washers, a load lifting arm protruding from one wall of said housing, means for oscillating said shaft to actuate said washers to ele-

vate said housing on said uprights and means for releasing said washers from frictional engagement with said uprights to lower said housing thereon.

5. In a lifting jack, a pair of uprights, a housing slidably longitudinally on said uprights and having a load supporting arm protruding therefrom, a pair of cooperating washers rockably mounted on said uprights in said housing, stabilizing springs bearing against the undersides of said washers, means journaled in said housing between said washers and engageable with each for alternately rocking the same to advance said housing along said uprights, means for actuating said latter means and means for disposing and holding said washers in a plane at right angles to the axes of said uprights to release and lower said housing on the latter.

20. 3. In a lifting jack, a pair of uprights, washers rockably mounted on said uprights, a spring bearing against the underside of each of said washers, a housing for said springs and washers, having a load engaging arm thereon, means oscillatably mounted in said housing effective to 25 alternate frictional engagement of said washers and their respective uprights to advance said housing on said uprights and means for releasing said washers simultaneously from said uprights to lower said housing thereon.

30. 4. A lifting jack comprising a base, a U-shaped member including parallel uprights, fastening means fixed to the base extending between the uprights, a housing slidably mounted on the uprights and having a load bearing member, cooperating friction climbing members rockably embracing the uprights within the housing, a substantially straight load transmitting shaft journaled in the housing between the uprights and shaped to engage the climbing members, where- 35 by a load on the housing may be transmitted directly to both climbing members by the load transmitting shaft, and springs for urging the climbing members upwardly.

45. 5. A lifting jack comprising parallel spaced uprights, a housing slidably mounted on the uprights, a load bearing member rigid with the housing, cooperating friction climbing members rockably embracing the uprights within the housing, a substantially straight load transmitting shaft journaled in the housing between the uprights and operatively engaging the climbing members whereby a load may be transmitted from the housing directly to both climbing members by the load transmitting shaft, and springs within 50 the housing for urging the climbing members upwardly on the uprights.
